HARRY HEITEL AND JOSEPH HEITEL, OF NEW YORK, N. Y., ASSIGNORS OF ONE-THIRD
TO HARRY JACOBSON, OF NEW YORK, N. Y.

VANITY CASE

Application filed July 24, 1928. Serial No. 294,955.

This invention relates to vanity cases and particularly, to the type adapted to store and dispense loose powder through suitable openings, and which type is known as the "sifter" 5 type.

Difficulty has been experienced in the past with sifter cases for the reason that the powder is not properly confined in the case and scatters about both in the case and outside 10 thereof, due to the lack of means for properly confining the loose powder. Another disadvantage is that if any unconfined loose powder remains in the dispensing compartment, it frequently reaches the mirror of 15 the case and prevents proper reflection by clouding the mirror. In none of the sifter cases heretofore in use is the loose powder automatically fed to the dispensing compartment, but said cases necessitate some additional manual operation such as tapping or 20 shaking the case or otherwise manipulating some parts.

Our invention contemplates the provision of means in which the objections above referred to are met, and in which a predetermined quantity of the powder is automatically fed for use into the dispensing compartment when the cover of the case is opened.

The various objects of our invention will 30 be clear from the description which follows and from the drawings, in which,

Fig. 1 is a top plan view of one form of our improved case.

Fig. 2 is a partial vertical central section 35 of the same.

Fig. 3 is a similar section taken on the line 3—3 of Fig. 1 and showing the fastening means for the movable parts in detail.

Fig. 4 is a plan view of a modified form 40 of the movable parts.

Fig. 5 is a vertical section of the same, taken on the line 5—5 of Fig. 4.

Fig. 6 is a top plan view of another modified form of connection for the moving parts.

Fig. 7 is a vertical central section of the same.

Fig. 8 is a perspective view of another modification as applied to a square or rectangular case.

Fig. 9 is a vertical section of the same.

Fig. 10 is a transverse section and front view of a portion of the same, showing the means for operating the dispensing blades.

Fig. 11 is a vertical section of a modified form of our improved case, showing another 55 form of means for operating the dispensing blades, and

Fig. 12 is a perspective view of the support for said blades showing the blades mounted 60 for swinging movement.

In the practical embodiments of our invention which we have illustrated by way of example, the case may be round, square or polygonal in outline and consists preferably of a lower member 10 provided with a loose powder storage compartment 11 and a dispensing compartment 12, and an upper member 13 hinged to the lower member by any suitable means as, for instance, the hinge 14. 65

A mirror as 15 may be suitably held in the 70 upper member 13 in a manner which is well known in the art, and hence which need not be described.

Referring now to Figs. 1 to 3 inclusive, we have there shown means for dividing the 75 lower case member 10 into two compartments 11 and 12.

Said means, as illustrated, consist preferably of a partition 16 fitted into the case member 10 and pierced with a plurality of 80 spaced openings as 17. A suitable flange as 18 may be depressed from the periphery of the partition 16 so as to contact with and to be held firmly in place in the case member 10. It will be understood that the flange 18 or 85 the partition 16 may be permanently soldered in place if desired, or that said partition and flange may be made of such dimensions as to fit frictionally into the case and to be removable therefrom, should it become necessary. 90

For feeding the loose powder in the storage compartment 11 through the openings 17, we prefer to provide a slide 19 preferably formed of sheet material. Apertures as 20 95 may be made in said slide by depressing the material therefrom at spaced intervals corresponding to the spaces between the openings 17 of the partition 16. Said depressed material is arranged in inclined position and 100

forms the dispensing blades 21. For manipulating the slide 19, the securing member 22, may be mounted upon the partition 16 and connected to the upper case member 13 as by means of the links 23 connected at one end to the angle 24, and at the other end, passed through a suitable ear or loop 25 in said member 22. Slots as 26 are made at the sides of the partition 16, through which the headed rivets as 27 are passed for securing the member 22 to the slide 19. Said rivets may be enlarged between the parts to maintain the spacing. A spring catch as 28 may be arranged in connection with the lower case member 10 to engage a suitable indent 29 in the upper case member 13 whereby said case members are maintained in their closed positions until opened manually.

It will be seen that when the case is opened, the links 23 pull the members 22 and the slide 19 connected thereto, toward the rear of the case. The inclined dispensing blades 21 are thereby moved to feed the loose powder in the storage compartment 11 up through the openings 20 and 17. Said openings are brought into registration in the open position of the case, so that the loose powder is fed through the registering openings to the dispensing compartment 12, and is readily accessible to the user. The powder in the dispensing compartment having been used up, there remains no loose powder in said compartment to cloud the mirror 15 or to spread about to soil surrounding objects, and no powder is wasted. On the closing of the cover 13, the slide 19 is pushed forwardly, allowing loose powder to shift above the blades when the case is moved or handled, as when it is placed in the purse. When the cover is closed, the apertures 17 are closed by the slide 19, so that no powder can reach the dispensing compartment 12 unless the case is opened.

In order to provide means for filling the powder compartment 11, we prefer to hinge the bottom 30 of said compartment about the hinge 31 and to provide a closing edge 32 about the periphery of said bottom to engage a corresponding edge on the remainder of the member 10, whereby leakage of powder is prevented. If desired, an annular bottom may be provided on the member 10, and the hinge 31 arranged inside of the periphery. In that case, the closing member 30 will be of less diameter than that of the member 10. We prefer, however, to make the outer diameters of the members 10, 13 and 20 equal so as to present a smooth outer surface on the case when it is closed. In any case, suitable lips may be provided on the members 30 and 10 between which a nail file or opener may be inserted to open the bottom more easily. It will be seen that the powder compartment can be filled quickly and easily by inverting the case and opening the hinged

bottom 30, and that at this time, the cover being closed, no powder can reach the dispensing compartment.

In the modification illustrated in Figs. 4 and 5, the top securing members 22 are dispensed with, and the links 23 are connected directly with the rivets 33. Said rivets are each provided with an upstanding head 34, suitable perforated for the reception of the end 35 of the link 23, the heads of said rivets being of sufficient diameter to engage the upper surface of the partition 16 and to guide the slide 19 in its movement relatively thereto.

As indicated in Figs. 6 and 7, the guiding rivets 27 and 33 may be dispensed with if desired, the slide 19 being held in proper sliding relation to the partition 16 by the projecting ends 36 thereof, passing through the slots 37 in the partition and being made longer than said slots so as to guide said slide 19 during its movement. In this construction, we have shown a single loop 38 replacing the support links 23. The operation of this form of our improved case, however, is the same as the modifications previously described and therefore need not be described further in detail.

Referring now to Figs. 8 to 12 inclusive, we have there shown a modification in which the integral inclined dispensing blades 21 are replaced by the swinging blades 39, so that the loose powder is positively fed through the space 40 between the blades up through the registering perforations, and into the dispensing compartment 12. As illustrated, said blades 39 are hinged at their extremities 41, to suitable depending projections 42 or the flange 43 depending from the slide 19. The bottom edges 44 of the blades 39 may be swung upwardly to force the powder there above through the openings 20 and 17 when said openings are in registration, by different means, such as is illustrated in Figs. 9 and 11.

As shown in Fig. 9, said means may consist of a plate 45 in which the arcuate cam slots 46 are made. Said plate 45 may be soldered or otherwise secured to the upstanding side of the bottom case member 10, or may be otherwise held in place, as may be found convenient or desirable. The slots 46 are adapted to receive a suitable projection as 47 on each of the blades 39 and to force said blades upwardly as the cover 13 is opened, since the slide 19 is drawn rearwardly on the opening of the cover and causes the projections 47 to move rearwardly and upwardly in said slots, thereby forcing any loose powder above said blades upwardly into the powder compartment as the openings 17 and 20 move into registration with each other.

As shown in Fig. 11, the plates 45 may be eliminated and the bottom 48 of the case so shaped as to provide cam surfaces which

have the same function as the slots 46 hereinbefore mentioned.

In either form of construction, as the cover is closed, the blades 39 are allowed by the slots 46 or the cam surfaces 49 of the bottom 5 48 to drop downwardly, the powder in the powder compartment shifting above said blades during the usual handling of the case as when returning it to a purse.

10 It will be seen that we have provided simple means operating automatically to feed a predetermined quantity of loose powder into a dispensing compartment as the case is opened, that the powder in our improved 15 case is normally confined in the powder compartment, and that protection against the flying about and waste of powder and soiling of articles near the case due to stray powder, is prevented.

20 It will further be seen that we have provided simple and efficient structure for carrying out the objects of our invention, which structure is well adapted to meet the severe requirements of practical use. While we 25 have shown and described certain specific embodiments of our invention, it will be understood that we do not intend to limit ourselves thereto but intend to claim our invention as broadly as may be permitted by 30 the state of the prior art and the terms of the appended claims.

We claim:

1. In a vanity case, a lower case member, an upper case member hinged thereto, a one-piece apertured and slotted partition dividing the lower member into a powder storage compartment and a dispensing compartment, and provided with a peripheral annular flange engaging said lower member, a slide disposed underneath the partition and having apertures adapted to register with the apertures in the partition when the case is open, a hinged bottom on the lower member adapted to engage the lower edge of said flange, whereby loose powder may be inserted into the storage compartment, the outermost parts of said case members and said bottom being flush in the closed position of the case to provide a smooth outer surface, 45 inclined blades projecting downwardly from the slide, a link holding member secured to the slide and passing through the slot of the partition, and a link connecting the link holding member to the upper member for operating the slide when the case is opened and for closing the dispensing compartment when the case is closed.

2. In a vanity case, a lower case member, an upper case member, an apertured partition dividing the lower member into a loose powder storage compartment and having a pair of spaced slots therein, and a dispensing compartment, an apertured slide associated with the partition, and means for operating said slide automatically to bring the apertures of

the slide and the partition into registration when the case is opened and to carry said apertures out of registration when the case is closed and for maintaining said slide and partition in operative engagement comprising a link pivotally secured at one end to the upper case member, means projecting above said slide through the slots of the partition and engaging the upper face of the partition for guiding the slide, and a perforated head on the projecting means for receiving the other end of the link.

3. In a vanity case, a pair of hinged case members, a slotted partition in one of said members, a hinged closure for one of said members, a movable member for forwarding powder associated with said partition, an upwardly projecting element on the movable member passing through the slots of the partition and engaging the upper face of the partition for maintaining the partition and the movable member in operative relation, and means in the other case member operatively connected to said first-mentioned means for moving the movable member when the case is opened and closed.

4. In a vanity case, a pair of hinged case members, a pair of relatively movable sheet metal members one above the other in one of the case members, a guiding member projecting from the lower sheet member past the upper sheet member, and a link pivotally secured to the guiding member and to the case member for causing relative movement of the sheet metal members on the opening and closing of the case.

5. In a vanity case, a pair of hinged case members, an apertured partition in one of said members, an apertured slide associated with the partition, powder forwarding blades pivoted to the slide, means for swinging said blades on the movement of the slide and means for connecting the slide to the other of the case members for moving the slide on the opening of the last-mentioned case member and causing the apertures of the slide and partition to register, and for moving the slide into initial position on the closing of the last-mentioned case member.

6. In a vanity case, a lower case member, a hinged closure member on said case member, a second case member, and powder forwarding means including a plurality of oscillatory blades in said first case member operated by the movement of said second case member.

7. In a vanity case, a perforated member fitted therein, blades pivoted to the partition for swinging movement below the member, a hinged bottom, and means for swinging said blades for feeding loose powder to points above the member on the opening of said case.

8. In a vanity case, a pair of hinged case members, a hinged bottom on one of said members for allowing the filling of said member with loose powder, powder feeding means

- in said member, and a link attached to and supported by said means and to the other case member for operating said means automatically on the opening of the case.
9. In a vanity case, a pair of hinged case members, a hinged bottom on one of said members, for allowing said member to be filled with loose powder, inclined blades pivotally mounted in said member, and means for moving said blades for forwarding powder to an accessible place in said member including a link removably attached to the other case member operatively connected to the blades.
10. In a vanity case, a pair of hinged case members of the same diameter, a hinged bottom on one of said members of the same diameter as said members, feeding means in said member operated by the opening of the case including inclined blades and a slide connected thereto, means for connecting the slide to the other case member a perforated partition above said slide, and a peripheral outer flange on said partition adapted to engage the bottom in the closed position thereof.
11. In a vanity case, powder advancing means, including oscillatory blades, and means for automatically operating said blades on the opening and closing of said case.
12. In a vanity case, a pair of hinged case members, a pierced partition in the lower case member dividing said member into a powder storage compartment and a dispensing compartment, a pierced slide below said partition, inclined blades projecting below said slide, and pivoted thereto and means connecting the slide to the upper case member for automatically reciprocating said slide on the opening and closing of said upper case member.
13. In a vanity case, a pair of case members, one divided into a powder storage and a dispensing compartment communicating therewith, and means for feeding powder from the storage to the dispensing compartment comprising oscillatory inclined blades operatively connected to the other of the case members and actuated thereby.
14. In a vanity case, adapted to be opened and closed feeding means for loose powder comprising a plurality of blades arranged in said case, and means for swinging said blades and operatively connected to said case for oscillating said blades on the opening and closing of the case.
15. In a vanity case, a pair of case members, powder feeding means in one of said members including inclined oscillatory blades, and means for operatively connecting said blades to the other of said case members.
16. In a vanity case, an outer annular member, a pair of case members hinged respectively to the top and bottom edges of the annular member, movable powder feeding means associated with one of said members; and means for automatically operating said feeding

means on the movement of the other of said members.

17. In a vanity case for dispensing loose powder, a swingable blade arranged in the case and moved to feed powder on the opening of the case.

HARRY HEITEL.
